UNITED STATES PATENT OFFICE.

WALTER D. COLEMAN AND WENSEL MORAVA, OF CHICAGO, ILLINOIS.

SIGNAL SWITCH.

Application filed April 17, 1922. Serial No. 553,519.

The purpose of this invention is to provide an improved construction in a switch device for controlling from the driver's seat the operation of a rear "stop-and-turn" signal or signals. It consists in the elements and features of construction shown and described, as indicated in the claims.

In the drawings:—

Figure 1 is a side elevation of a portion 10 of an automobile equipped with this invention.

Figure 2 is a rear end elevation showing the stop and turn signals in their position on the vehicle.

15 Figure 3 is a section at the line, 3—3, on Figure 1, showing the switch-controlling device of the invention in plan view.

Figure 4 is a section at the line, 4—4, on Figure 1, showing the rear side plan view 20 of the support of the switch controller and parts thereon.

Figure 5 is a section at the line, 5—5, on Figure 3.

25 Figure 6 is a section at the line, 6—6, on Figure 5, comprising also a diagram of the wiring.

In the structure shown in the drawings, the fixed standard of the steering column is seen at 1. 2 is the steering hand wheel. 30 2 is its shaft. 4 is a support for the circuit controller which is clamped onto the standard, 1. 5 is a circuit controller which is pivoted upon the support, 4, on the pivot, 6, which is of conducting material, said support, 4, and the circuit controller being preferably of insulating material, and to be so understood in the drawings. The circuit controller, 5, is retained on the pivot, 6, and held pressed firmly against the support, 4, 35 by a spring, 8, footed on a washer, 9^a, and coiled around the projecting upper end portion of the pivot for reacting between a metal plate, 7, which is secured upon the upper side of the circuit controller, 5, and a washer, 9, above the spring, checked on the pivot by a cotter pin, 10, the spring being compressed to any desired tension in bringing the washer 9, down on the pivot to a point which permits the cotter pin to 40 be inserted above it. The controller, 5, carries two contacts, 11, 11^a, projecting from its lower side and spring-pressed downward by springs, 11^b, 11^b, which at their upper ends react against the under side of the plate, 7, against which, as stated, the lower washer, 9^a, is pressed by the spring, 8, there- 45 by effecting electrical connection between the pivot, 6, and the contacts, 11. In the upper surface of the support, 4, there are embedded, flush with said upper surface, annular contact plates, 12, 13 and 14. The contact plate, 12, is a complete annulus, except as to a short gap, 12^a. The plates, 13 and 14, are similar segments of an annulus 50 outside the annulus, 12, and concentric therewith, said annular segments, 13 and 14, being separated by a gap, 13^a, in radial relation to the gap, 12^a, of the plate, 12, and being also separated by a short gap 13^b, diametrically opposite said gap, 13^a. The contact plate, 12, is in the path of the lower end of the contact, 11, and the annular segments, 13 and 14, respectively the paths of the contact, 11^a, in the rotation of the controller, 5, to the right and left, respectively. 55 The controller, 5, is provided with gear teeth, 5^a, 5^b, and 5^c, for engagement by teeth, 3^b, of a mutilated gear member, 3^a, which is carried by the shaft, 3, of the steering hand wheel. At the straight-ahead position of the steering hand wheel, the tooth, 5^a, of the controller, 5, is engaged between the teeth, 3^b, the parts being in the position seen in Figure 3. Upon the rotation of the steering wheel to the right for turning the vehicle to the right, the controller, 5, is turned through an angle of about 30 degrees, and is not further rotated throughout the remainder of the first revolution of the steering hand wheel. If steering movement 60 of the wheel continues in the second revolution, the tooth, 5^b, is engaged, and the controller is further rotated through another 30 degrees. In the first thirty degrees of the second revolution, and upon the first 65 return revolution of the steering hand wheel, the controller is picked up by the engagement, first of the tooth, 5^b, and afterward, by the engagement of the tooth, 5^a. And, similarly, in rotation of the steering hand wheel to the left, the controller is turned thirty degrees in the corresponding direction in the first thirty degrees of the first revolution of the steering hand wheel, and thirty degrees additional in the first thirty 70 degrees of the second revolution of the steering hand wheel, and is restored to initial position in the reverse movement of the steering wheel to straight-ahead position. 75 The switch and controller devices above 75 described are connected in three circuits comprising a main circuit, and two branch

circuits. All said circuits are energized by a single source of energy as the battery indicated at X, mounted in any convenient position on the automobile, from which the line wire, 15, leads to a binding nut, 15^a, on the rear end of the pivot, 6. A binding screw, 16, rooted in the contact plate, 12, and extending through the support, 4, at the rear side thereof, is connected by a line wire, 17, with the rear stop signal, S, which is in turn grounded by connection to the vehicle frame work, as indicated by the "ground", D, in diagram, Figure 6. From the annular segment contact plate, 13, a line wire, 18, leads to the right-hand signal, R, which is in turn grounded, as indicated in diagram, Fig. 6, the connection of the line wire, 18, to the segment, 13, being by means of a binding post, 20, rooted in said segment and extending through the support, 4, to the back side thereof, as seen in Figure 5. Similarly, the segment contact annulus, 14, is provided with a binding post, 21, from which a line wire, 22, leads to the left hand turn signal, L, which is in turn grounded, as seen in Figure 6. It will be seen from the foregoing description, that the several circuits being completed by contact of the contacts, 11 and 11^a, with segments, 13 and 14, according to the position of the circuit controller, the pivot, 6, will be contained in all the circuits, the stop signal will be contained in the circuit with the contact plate, 12; the right-hand turn signal will be contained in circuit with the contact plate, 13, and the left-hand turn signal will be contained in circuit with the contact plate, 14; and that at the normal or straight-ahead position of the steering handle, all these circuits will be open by reason of the contacts, 11 and 11^a, standing at the gaps, 12^a and 13^a, between the proximate ends of the contact plates, but that upon turning of the steering hand wheel a very few degrees either to the right or to the left, the circuit containing the stop signal and the plate, 12, will be closed and the stop signal energized; that if the turn has been to the right, the circuit containing the right-hand-turn signal and the contact plate, 13, will be simultaneously energized, causing the right-hand signal to be illuminated, but if the turn has been to the left, the circuit containing the plate, 14, and the left-hand-turn signal will be energized, and said left-hand signal will be illuminated. It will be understood also that the signal to be energized and illuminated by the turn in one direction or the other will continue to be illuminated until the steering hand wheel is returned to straight-ahead position.

It will sometimes be considered desirable to signal the intention to turn to the right or to the left before the steering hand wheel is operated for making the turn. In order 65 to afford means for doing this, each of the

circuits containing respectively the plates, 13 and 14, and the right and left hand turn signals is provided with a shunt or by-pass around the gap, 13^a, between the plates, 13 and 14, and means for closing this gap at will. For this purpose there are extended upon the back side of the support, 4, from the binding posts, 20 and 21, respectively, conducting wires 25, 25, to contact terminals, 26, 26, mounted upon the back side of the support; and from the pivot, 6, wires, 27, 27, are extended to contact terminals, 28, 28, mounted upon the back side of the support proximate to and out of contact with the terminals, 26, 26, respectively. Journaled in and extending through the support, 4, are rock shafts, 30, 30, having at their rear ends switch contact arms, 31, 31, lapped across and making electrical contact between the terminals, 26 and 28. At their forward ends these rock shafts have fingers or operating lever arms, 32, 32, or other suitable means of turning them, and also extending close over the base of the controller, 5, said rock shafts have each a lever arm, 33; and the controller, 5, has projecting from its forward upper face co-operating studs, 34, 34, positioned for encounter with the arms, 33, 33, respectively, according as the controller is turned to the right or the left. The normal position of these rock shafts with their respective lever arms and switch contacts, is with the said contacts, 31, in the position shown in Figure 4, that is, out of contact with the contact terminals, 26 and 28, leaving the by-pass or shunt circuit open. The arms, 33, 33, being at that position of the rock shaft at the position seen in Figure 3, out of the path of the studs, 34, 34, on the controller. If the operator wishes to give the premonitory signal that he intends to turn to the right, he will by means of the handle lever arm, 32, turn the right hand rock shaft, 30, through an angle of about 45 degrees, which will close the gap of the by-pass or shunt leading to the right-hand-turn signal and will cause that signal to be energized. Or if he wishes to give warning of the intention to turn to the left, he will similarly operate the left hand rock shaft, 30, closing the by-pass or shunt of the circuit containing the left-hand-turn signal. When, immediately after giving the premonitory warning, the operator turns the steering hand wheel for making the turn, the stud, 34, carried by the controller, encountering the lever arm, 33, turns the rock shaft which has been operated for giving the premonitory warning, back to normal position, opening the by-pass, at the same time that the direct circuit is closed, will thus cause the signal to be continued in operation, but obviating the necessity for the operator remembering to open the by-pass when the turn has been completed, and thereby insuring that the

"turn" signal will not continue to be energized after the turn is completed.

We claim:-

1. An electric switch device comprising in combination with a rotatable part, a support adapted to be secured fixedly with respect to said rotatable part; a contact carrier; an electrically conductive pivot on which the carrier is mounted, said pivot being mounted on said support; two contacts insulated on the carrier, both in circuit with said pivot; a pair of contact plates insulated from each other on the support; a third contact plate insulated from the pair, said pair and said third contact plate extending respectively in the paths of the contacts carried by the carrier, the two plates of the pair extending from the interval between them in opposite directions along said path; two circuits each containing one plate of the pair; a third circuit containing the third plate, and means by which said rotatable part turns the contact carrier in one direction or the other from non-contact position of the contact which it carries, as the rotatable part is turned in one direction or the other from a selected normal position.
2. An electric switch device comprising in combination with a rotatable part a support secured fixedly with respect thereto; a switch controlling device mounted on the support and engaged with the rotatable part for turning in one direction or the other, as said rotatable part is turned; a contact carrier and an electrically conductive pivot on which said carrier is mounted; three electric circuits; contacts on the support and co-operating contacts on the carrier for closing the first of said circuits upon turning of the rotatable part in either direction away from a selected normal position, and for closing the second circuit upon turning said rotatable part in one direction, and the third circuit upon turning it in the other direction.
3. In the construction defined in claim 2 foregoing, the second and third circuits having each a shunt or by-pass branch with a gap and a switch for closing said gap; said switches being manually operable independently of the turning of the rotatable part and having each an arm which when the switch is in closed position extends over the rotating contact carrier, and means on said carrier for engaging said arms for turning the switches respectively back to open position by the turning of the carrier in the direction for closing the main circuit whose shunt branch or by-pass is thus opened.
4. An electric switch comprising in combination with a rotatable part, a support adapted to be secured fixedly with respect to the axis of rotation of said rotatable part; a switch controller pivoted on said support; an electric circuit in which the pivot is contained comprising three branches; contacts carried by the switch controller in circuit with said pivot; contact plates on the supports comprising a pair of such plates in the path of movement of one of the contacts carried by the controller, and a single plate in the path of the other contact, the single plate being in one of the circuit branches and the two plates of the pair being extended in opposite directions from the interval between their proximate ends, and being one in a second branch circuit and the other in a third branch circuit; the contacts on the controller being both out of contact with the contact plate on the support at a selected normal position of the rotatable member, and means by which the turning of said rotatable member from said normal position turns the controller to carry the contacts thereon into contact with the plates respectively.
5. An electric switch device comprising in combination with a rotatable member, a support secured fixedly with respect thereto, three electric circuits, a circuit controller mounted for rotation by said rotatable member and co-operating circuit-making-and-breaking contacts on said controller and support arranged for openness of all said circuits at a selected normal position of the rotatable member, and for closure of one of said circuits by rotation of said rotatable member in either direction from said normal position, and for closure of a second of said circuits by rotation of said member in one direction from said normal position and of the third of said circuits by rotation in the opposite direction from said normal position.
6. In the construction defined in claim 5, foregoing, the second and third circuits having each a shunt or by-pass around the gap existing at the normal position of the rotatable member; a manually operable switch device in said by-pass adapted to be closed at will independently of the rotation of said rotatable member, and means on the controller for reversely operating said last mentioned switch to open the by-pass upon turning said rotatable member in either direction from said normal position.
7. In the construction defined in claim 4 foregoing, the contact carrier being of insulating material whereby the conducting parts therein and thereon are normally insulated from each other; a metal plate on the outer side of the controller through which the pivot extends in contact therewith, the contacts carried by the controller being spring-pressed toward the contact plates of the support by springs reacting against said metal plate.
8. In the construction defined in claim 4, foregoing, the supports being of insulating material, whereby the contact plates thereon and the controller pivot projecting therefrom

are normally insulated from each other merely by being out of contact with each other, the controller being also of insulating material for insulating from each other the contacts carried thereby, said controller having a metal plate on its upper side through which the pivot extends in contact therewith, the contacts carried by the controller being in touch with said plate; a spring on the pivot above the controller, seated at its lower end on said plate, and a stop on the pivot for tensioning the spring to maintain electric contact thereof with the plate.

9. A switch for controlling movement-indicating signals and the like on a motor vehicle comprising in combination with a part which is rotated for control of the vehicle, a supporting member adapted to be secured to a fixed part of the vehicle, a contact carrier, a pivot on which the contact carrier is mounted, two contacts insulated in the carrier both in circuit with the pivot, a pair of contact plates insulated from each other, a third contact plate insulated from the pair, said pair and said third contact plate extending respectively in the paths of the contacts carried by the carrier, the two plates of the pair extending from the interval between them in opposite directions along said path; two circuits each containing one plate of the pair; a third circuit containing the third plate; means by which the rotated part turns the contact carrier on its pivot; a stop signal device in the third circuit, and right and left turning signals in the other two circuits respectively.

10. In combination with the construction defined in claim 1 foregoing, the same being mounted on a motor vehicle, the support being fixed with respect to the vehicle body and the rotatable part being a part which is rotated for steering the vehicle; a stop signal in the third circuit and right and left hand

turning signals in the other two circuits respectively.

11. In combination with the construction defined in claim 2 foregoing, the same being mounted upon a motor vehicle, the support being fixed with respect to the vehicle body and the rotatable part being a part which is rotated for steering the vehicle, the second and third circuits having each a shunt or by-pass branch with a gap and a switch for closing said gap, said switches being manually operable independently of the turning of the rotatable part and having each an arm, which, when the switch is in closed position, extends over the rotating contact carrier, and means on said carrier for engaging said arms for returning the said switch back to open position by turning the carrier in the direction for closing the main circuit whose shunt branch or by-pass is thus opened.

12. In the construction defined in claim 4 the same being mounted upon a motor vehicle, the support being fixed with respect to the vehicle body and the rotatable part being a part which is rotated for steering the vehicle; a stop signal in the third circuit, and right and left hand turning signals in the two other circuits respectively.

13. In combination with the construction defined in claim 5 foregoing, the same being mounted upon a motor vehicle, the support being fixed with respect to the vehicle body and the rotatable part being a part which is rotated for steering the vehicle; a stop signal in the third circuit and right and left hand turning signals in the other two circuits respectively.

In testimony whereof, we have hereunto set our hands at Chicago, Illinois, this 14 day of April, 1922.

WALTER D. COLEMAN.
WENSEL MORAVA.
